S. R. FRAIM.
WARD CYLINDER FOR LOCKS.
APPLICATION FILED JULY 16, 1917.

Patented Jan. 15, 1918.

Inventor

Samuel R. Fraim

By D. M. Fraim

Attorney

UNITED STATES PATENT OFFICE.

SAMUEL R. FRAIM, OF LANCASTER, PENNSYLVANIA, ASSIGNOR TO THE E. T. FRAIM
LOCK COMPANY, A CORPORATION OF PENNSYLVANIA.

WARD-CYLINDER FOR LOCKS.

1,253,678.

Specification of Letters Patent. Patented Jan. 15, 1918.

Application filed July 16, 1917. Serial No. 180,714.

To all whom it may concern:

Be it known that I, SAMUEL R. FRAIM, a citizen of the United States, residing at Lancaster, in the county of Lancaster and 5 State of Pennsylvania, have invented certain new and useful Improvements in Ward-Cylinders for Locks, of which the following is a specification.

This invention relates to ward cylinders 10 for locks.

Heretofore cylinders of this kind when formed of sheet metal, have been made with a solid wall and therefore the wards contained in them have of necessity been held 15 in place by castings or washers which are difficult of introduction and which are more or less insecure in their positions when seated.

The object which I have in view is to 20 provide a ward cylinder which shall be cheap and easy of manufacture and which shall be of a form to permit of the rapid placing of wards permanently therein with the expenditure of little labor.

25 With this object in view the invention consists of a ward cylinder having the novel generic and specific features substantially as hereinafter described and claimed.

The invention is illustrated in the accompanying drawing in which;

Figure 1 is a perspective view of a ward cylinder applied to the cap of a lock case; and,

Fig. 2 is a vertical sectional view of the 35 cylinder showing two wards arranged therein.

The cylinder is made from a sheet of metal by drawing the two ends of the sheet down into a forming die, producing the 40 cylindrical body and the circular flange extending substantially at right angles to the body.

The cylinder when completed is composed of two parts 1 and 2 of the same size each 45 forming half of the cylinder and each half has formed with it a semi circular base 3.

The semi-cylindrical parts of the body of the cylinder and base are separated from each other throughout except that they are connected by the outer end portion 4 the outer face of which is preferably depressed presenting the outer rounded face 6 as shown, and has formed in it a key opening 7.

Each part of the wall of the body of the

cylinder is provided with one or more openings or sockets 8 of any desired form, being preferably angular, oppositely arranged, and adapted to receive the projections 9 extending from the peripheries of the wards 10. The projections are of a form in cross section corresponding to the shape of the openings in the sides of the cylinder. The openings and projections are each preferably angular or other than circular in cross section to prevent turning of the wards when 65 introduced and seated.

In placing the wards in a cylinder constructed as described, the parts of the body of the cylinder are drawn apart, the wards introduced and the projections therefrom 70 properly placed in the openings or sockets in the sides of the cylinder. The parts of the cylinders are then brought toward each other until their edges meet and the cylinder is then attached in place for use by 75 screws or rivets, passed through the flange, for instance to the cap of a lock case as herein shown.

The cylinder described is not only cheaper than those heretofore made but its construction 80 permits of the more rapid introduction and holding in place of the wards without the use of any additional parts. Furthermore when the wards are arranged in the cylinder as described, and the base of the 85 cylinder is secured in place displacement of the wards is impossible.

I claim:

1. A ward cylinder formed of one piece of material bent and drawn into two separate semi-cylindrical parts, and an outer end portion connecting the said parts.

2. A ward cylinder formed of one piece of material bent and drawn into two separate semi-cylindrical parts and an outer end portion connecting said parts, each of said parts being provided with opposed openings, and wards having projections adapted to enter said openings, said semi-cylindrical parts being adapted to be drawn apart to permit 100 the insertion of the wards and to be brought together to hold the wards in position.

In testimony whereof I affix my signature in presence of two witnesses.

SAMUEL R. FRAIM.
